BUOYANT SOAP HOLDER

Walter J. Zawadzki, Cheektowaga, N. Y.

Application April 9, 1946, Serial No. 660,753

2 Claims. (Cl. 45—28)

1

My invention relates to a soap holder, and more particularly to a buoyant holder designed especially to hold cakes of soap of various sizes while the holder is buoyantly supported by water within a bathtub.

I am aware of the fact that there is provision made in various ways adjacent bathtubs, for holding or retaining soap, but the soap so held or retained is not always easily accessible from the different positions assumed while taking a bath. Non-floating soap, when used for bathing, results in encountering difficulties in locating the soap, and floating soap, while always seen and readily accessible, becomes soft and is, therefore, used excessively and quickly consumed.

It is one of the objects of my invention to provide a buoyant soap holder which will float on the water within a bathtub and retain the soap without any portion thereof being submerged in water; thus resulting in the economical use of soap, due to the fact that it is maintained in comparatively dry condition.

Another object of my invention is to provide a buoyant non-tipping soap holder in which the center of gravity is such that a cake of soap casually or carelessly placed or flipped into the holder will become centered therein; both with respect to its length and width and thus guard against tipping of the holder while floating on the water.

Another object of my invention is to provide a buoyant soap holder which can be used for general purposes, by associating therewith a suitable bracket or support from which it can be easily removed and placed within a bathtub so as to float on the water within the tub and render the soap easily accessible when taking a bath.

A still further object of my invention is to provide a holder having a depressed soap-receiving space or chamber and an air-tight surrounding casing into which the depressed portion extends so that the center of gravity or the center of flotation is beneath the surface of the water when the holder is buoyantly supported by the water.

A still further object of my invention is to provide a soap holder having a marginal top wall, a bottom wall and end and side or vertical walls constituting an outer casing, and a depressed soap-retaining portion extending downwardly from the inner edges of said marginal top wall so as to have a depth greater than one-half the height of said vertical walls and wherein said depressed soap-retaining portion serves as an inner casing, completely closing said outer casing

2

and having its side and end walls sloping downwardly and inwardly, and further wherein said depressed portion has a bottom wall parallel or substantially parallel with and spaced from the bottom wall of said outer casing, thus providing an air-space which surrounds said depressed portion and extends underneath the same.

A still further object of my invention is to provide a soap holder with a bead around its perimeter for association with a loop forming part of a bracket into which the soap holder is to be placed so that the loop supports the holder by contact with said bead and in which said loop is provided with means for suspending or supporting the same with the soap holder removable therein.

A still further object of my invention is to provide a soap holder stamped of sheet metal and comprising a lower part and an upper part, said upper part being seamed to said lower part in an air and water-tight manner and said upper part having a depressed portion extending well into said lower part, said lower part and said upper part each being so formed that when joined together, an air-space is provided between the two parts so as to render the soap holder buoyant.

With the above and other objects in view to appear hereinafter, my invention consists of the novel features of construction, and in the arrangement and combination of parts to be hereinafter described and more particularly pointed out in the subjoined claims.

Fig. 1 is a perspective view of my improved soap holder, showing the same supported by a bracket adapted to be suspended from a wall or other upright object.

Fig. 2 is a detached perspective view of the bracket designed to hold the soap holder proper.

Fig. 3 is a transverse section of the soap holder showing the same supported within the bracket.

Fig. 4 is a vertical longitudinal section of the soap holder, the bracket for the same being omitted.

Fig. 5 is a longitudinal section through a holder embodying my invention in modified form.

When forming the holder in preferred form, it is stamped of sheet-metal and comprises a lower part 6 and an upper part 7. The lower part 6 is formed into a comparatively deep tray-like portion having an imperforate bottom wall 8, vertical walls in the form of side walls 9 and end walls 10; it being open at the top. The upper part 7 is formed into a soap chamber 11, having concaved downwardly-inclined side walls

12, straight lined downwardly-inclined end walls 13 and an imperforate bottom wall 14. At the upper ends of the side walls 12 and end walls 13 the metal is directed outwardly to form a flange 15 parallel with the bottom walls 8 and 14 and serving as the top wall of the holder and it is thence bent downwardly to form peripheral depending wall portions 16 in spaced relation to the upper portions of the downwardly inclined walls 12 and 13.

Near the lower ends of the depending wall portions 16 an outwardly-extending bead 17 is formed which is continuous around the four depending wall portions 16. The lower ends of the latter are offset inwardly to form flanges 18 beneath said bead. When joining the upper and lower parts of the holder, the flange 18 fits snugly within the upper portions of the vertical or side and end walls 9 and 10 of the lower part and the upper edges of said walls bear against the bead 17 of the upper part. Thus assembled, the seam formed between the lower and upper parts is soldered or brazed so as to render the device air and water-tight. The side and end walls 9 and 10 and the bottom wall 8 of the lower part, taken with the flange 15 and the depending portions 16 with the bead 17 and flanges 18 may be considered an outer casing, while the soap chamber 11 depressed into said outer casing may be considered the inner casing of the holder.

Due to the fact that the depressed portion forming the soap chamber extends down into the outer casing a distance below the horizontal center of the latter, the plane or line of flotation is, therefore, below the horizontal center of the device when unweighted and floating on a body of water and it may here be stated that the space 19 between the inner and outer casings serves as an air-space.

When the two parts of the device are joined together in the manner stated, or in any other approved manner which will render the device air and water-tight, the holder will be rendered non-tipping with or without a cake of soap placed in the soap chamber. Thus the soap will be kept in comparatively dry condition so that when a cake of soap is placed in the soap chamber, it will not become soft and consequently will not wear away easily with use. This results in economy in the use of the soap and enables the cake of soap to be applied to the bath-brush or other medium used in bathing without excessive application of soap.

Moreover, when the empty soap holder is floating on the water within a bathtub and the plane or line of floatation is beneath the level of the water, flippant entry of the soap into the soap chamber may move the holder from a position of quiescence, but the cake of soap will find its central position within the soap chamber without causing the holder to tip within the water. By having the bottom of the soap chamber imperforate, no water can enter from below and only water adhering to the soap and flowing therefrom may enter and thus the weight of the welding will not unduly effect the buoyancy of the device.

It is to be noted in Fig. 3 that soap of two different sizes are shown in dotted lines, the heavy dotted lines 20 designating a small cake of soap, while the lighter dotted lines 21 designate a comparatively large cake of soap. In each instance, due to the inclination given the side and end walls of the soap chamber, the cake of soap will center itself within the soap chamber and thus retain the soap holder in horizontal position,

particularly since the soap chamber is centered both transversely and longitudinally.

Brazing of the two parts of the soap holder together is effected in a manner that will not deform the shape of the bead 17 formed on the upper part of the holder, said bead being adapted for contact with a bracket 22, which may be constructed of wire bent into the shape of a loop 23 conforming to the outline of the soap holder. 10 In the bracket shown, the ends of the wire forming this loop are secured to a fastening device in the form of a plate 24, having openings 25 formed therein for screws to fasten the bracket to a wall or other vertical object, or it may be secured to the wall or other object of any other approved manner.

The utilization of this bracket in connection with my improved soap holder is to enable the latter to be used for general purposes as well as for use within a bathtub, since the bracket may be fastened in place above a wash-stand and the soap holder suspended therein so that the latter may be easily removed from the bracket and utilized for bathing purposes when desired. It is, of course, understood that the buoyant qualities of the soap holder are not utilized when the latter is used in conjunction with the bracket and it will be apparent that it requires only an upward pressure against the bottom of the soap holder in order to loosen and remove the same from the bracket.

As clearly shown in Figs. 1 and 3, the bead 17 of the soap holder serves as a support or rest for the latter when placed within the bracket, since this bead lies in contact with the four sides of the wire loop 23 and thus carries the weight of the soap holder and the cake of soap therein.

In the modification shown in Fig. 5, my invention is embodied in a holder formed of plastic material and in this instance the walls of the outer casing and the soap chamber are integral. In the preferred construction above described, the vertical or side and end walls 9 and 10, the bottom wall 8 and the marginal top wall 15 constitute the outer casing of the soap holder while the downwardly-inclined side walls 12, the downwardly-inclined end walls 13 and the bottom wall 14 constitute the inner casing, otherwise referred to as the soap chamber. In this modification, as well as in the preferred construction above described, the air-space 19 between the two casings extends both underneath the soap chamber as well as around the latter and I wish to stress that the formation of an air-space between the bottom walls of the outer and inner casings is of decided importance since it renders the soap holder more buoyant and aids materially against any tipping action of the soap holder under careless entry of the soap into the latter, particularly when such an entry is made under flippant action of the bather. Parts in this modification which are similar to parts of the preferred construction are designated by similar numerals of reference.

Having thus described my invention, what I claim is:

1. A buoyant soap holder, comprising a deep tray-like lower member having a bottom wall and side and end walls, and a top member having a soap chamber provided with an imperforate bottom wall, side and end walls, a marginal top wall extending outwardly from the upper ends of said last-mentioned side and end walls and depending portions extending from said marginal top wall, said depending portions having an outwardly projecting bead near their lower ends and having

the portions thereof beneath said bead offset inwardly with respect to the portions thereof above said bead, said offset portions being entered in said lower member and the upper edges of the side and end walls of said lower member being in contact with said bead, the seam thus formed between said members being rendered air and water-tight and said bead projecting outwardly beyond the outer surfaces of the side and end walls of said lower member to serve as a stop when the holder is slipped into a bracket or support, and an air chamber beneath the soap chamber and entirely around the same.

2. A non-tipping soap holder to be used buoyantly in a body of water, said holder having a bottom wall, vertical walls rising from said bottom wall, a top wall extending a short distance inwardly from said vertical walls and a soap chamber depending from said top wall in spaced relation to said vertical walls and said bottom wall so as to provide an air-space between said soap chamber and said vertical and bottom walls, the bottom wall of said soap chamber being imperforate and on a level beneath the surface of the

water in which said holder is buoyantly supported, the structure so formed being air and water-tight and its changing plane of floatation, depending on its welding, being arranged so as to prevent tipping of the device when floating on water.
